HOLLOW CONSTRUCTIONAL BLOCK

Pierre Norbert Paquet, Uccle, Belgium

Application March 19, 1948, Serial No. 15,936

Claims priority, application Belgium April 11, 1947

7 Claims. (Cl. 72—41)

The present invention relates to a hollow structural block comprising vertical longitudinal walls which are connected together by means of vertical transverse walls.

In the present specification, it is necessary to understand by "vertical longitudinal walls" or "longitudinal walls" the walls which are parallel to the front faces of a wall constructed by means of blocks in accordance with the invention, and it is necessary to understand by "vertical transverse walls" or "transverse walls," the vertical walls which are perpendicular to the longitudinal walls. The two other walls of the hollow block according to the invention are called "horizontal walls."

Up to the present, when a structure is being made by means of hollow blocks of a known type, these are built up with mortar in a manner similar to that used for bricks or masonry.

The purpose of the present invention is to make possible the easy construction of walls by means of blocks connected together in a solid manner by means of mortar without it being necessary to have recourse to a large amount of skilled labour.

This result can be produced by employing constructional blocks in which the transverse walls are provided over their whole height with cavities which terminate in channels formed in at least one of the horizontal faces between which these cavities extend, and as far as into at least one of the longitudinal walls, the said channels terminating in a hole formed over the entire height of the block at a distance from the middle plane of a neighbouring transverse wall which is equal to the half of the distance between the middle planes of two adjacent transverse walls of the block.

According to an advantageous form of construction in the case of a block of parallelepiped form provided with a transverse wall at mid-length and with a transverse wall at each end, a cavity is formed in the medial transverse wall, whilst grooves or slots are formed in the end transverse walls, so as to form a cavity by the juxtaposition of the extremities of two blocks, and in addition, the above-mentioned channels terminate in holes of the kind mentioned which are formed in one only of the longitudinal walls at a distance from each end equal to a quarter of the length of the block.

In order to construct a wall by means of blocks of this kind, a commencement is made by superposing a certain number of layers of blocks, which for preference have been previously damped. This superposition is carried out without mortar, and in such a way that the holes mentioned above register with one another. A workman then introduces a bar into the superposed holes, the dimensions of this bar being such that it rectifies the alignment of the holes if the latter do not register quite correctly. This bar is of such a form that there remains, between it and the sides of the holes in which it is engaged, a space which permits the escape of air when mortar is poured in, as will be indicated hereinafter. The bar is moreover of such a form that it does not allow the mortar to flow past the holes in which the bar is engaged. An assistant then pours mortar in very liquid condition into the cavities situated at one side of the holes into which the above mentioned bar passes. When the casting reaches the upper level of the wall under construction, all the blocks are automatically connected together in rigid manner at the side of the bar where the casting has taken place, owing to the fact that the said channels are filled up with mortar. After each casting operation, the operator withdraws the bar from the holes

2

into which it has been engaged and introduces it into the succeeding holes. Consequently the holes which are freed from the bar are filled up in turn when mortar in very liquid condition is poured into the cavity located between the holes freed from the bar and those in which it is now engaged. The air contained in the channels can escape freely through these two types of holes. When the same operations of casting have been carried out over the whole length of the wall, a number of layers of blocks is again placed without mortar in the same way as has been already mentioned.

The longitudinal and transverse walls serve as shuttering for reinforced concrete columns serving as a framework for the wall. If it is desired to increase the size of these columns of reinforced concrete, one of the longitudinal walls can easily be replaced by a mass of reinforced concrete integral with that of the adjacent column by demolishing with a chisel areas of less thickness in the longitudinal wall opposite to that in which the said holes are formed, in the neighbourhood of the transverse walls.

Other features and details of the invention will appear in the course of the description of the drawings accompanying the present specification, which show diagrammatically and by way of example only some forms of realisation of the invention.

Figure 1 is a view in perspective, partly broken away, of a form of construction of a structural block in accordance with the invention, the upturned face of which corresponds to the lower face of the block in its position of use.

Figure 2 is a view in perspective of a part of a shuttering which is intended to be used in combination with blocks such as that of Figure 1, and certain parts of which would be removed.

Figure 3 is a cross section through a bar which acts in conjunction for the setting of the blocks according to the invention.

Figures 4 and 5 each represent a plan view of a block according to the invention seen at the lower face.

In these various figures, the same reference numerals designate the same elements.

The structural block shown in Figure 1 is a block of parallelepiped form, comprising vertical longitudinal walls 2 and 3, which are connected together by vertical transverse walls 4, 5 and 6.

The transverse wall 5 is disposed at mid-length of the block, and the walls 4 and 6 at the ends of the block. A cavity 7 extending throughout the entire height of the block is formed in the middle transverse wall, whilst grooves or slots 8 and 9, possessing in cross section half the cross-sectional area of the cavity 7, are formed in the end transverse walls 4 and 6, so as to form a cavity similar to the cavity 7 by the juxtaposition of the extremities of two blocks. The cavity 7 and the slots 8 and 9 terminate or open into channels 10 formed in the lower horizontal face. These channels extend from the transverse walls into the longitudinal wall 2 as far as two holes 11 formed throughout the whole height of the block at a distance from each end of the latter equal to a quarter of the length of the block.

The longitudinal wall 3 opposite to the longitudinal wall 2 in which the holes 11 are formed is of less thickness in the vicinity of the transverse walls 4, 5 and 6. This smaller thickness is produced on the one hand by the presence of passages 12 at a slight distance from the outer face of the longitudinal wall 3, and on the other hand by the presence of grooves or slots 13 on the outside face of this same longitudinal wall.

The partitions or tongues of material 14 between the passages 12 and the slots 13, and also the partitions or tongues 15 between the passages 12 and the hollows 16 formed between the longitudinal and transverse walls, can easily be demolished by means of a chisel. If only the partitions 14 are removed, there is available through the union of the slots 13 with the passages 12, shafts in which lines such as electric wiring can be placed. If both the partitions 14 and 15 situated between two adjacent transverse walls are removed, there is available, for the location of reinforced concrete to serve as a framework for the structure, a cross-sectional area which

is substantially greater than that corresponding to the cross section of the adjacent hollow 16. During the placing of this reinforced concrete, the longitudinal wall 2 and also the adjacent transverse walls act as shuttering for the concrete. The other wall of the shuttering of the column may be formed by a double plank 17 (Figure 2), the opposite edges of which can be held in place by bevels 18 and 19, which converge towards the outside and which form the external side faces of two grooves or slots 13 formed in the part of the longitudinal wall 3 between two adjacent transverse walls.

When the two planks 17 have been introduced between the bevels 18 and 19, they can easily be held in place for example by means of a latch formed by a bar 20 lodged in hooks 21 fixed to the planks 17.

When different layers of blocks according to the invention have been superposed so that the holes 11 form an upright chimney, the correct alignment can be obtained by introducing into the superposed holes 11 a bar 22 such as that shown in Figure 3. In this bar, the diameter of which is slightly less than that of the holes 11, are formed longitudinal grooves 23. It would also be possible to use a rod of polygonal section inscribed in a circle corresponding to the cross section of the holes 11.

If, instead of removing the partitions 14 and 15 over the whole height of the blocks, they are only removed at one of their extremities, it is easily possible to form passages for metallic reinforcements, which will form part of horizontal beams of reinforced concrete in relation to the vertical reinforced concrete columns the shuttering of which is formed by the vertical walls of the blocks. Other parts of the longitudinal walls 3 may be of smaller thickness. This is the case for instance with the parts 24 in the middle of the length of the parts of the longitudinal walls between two adjacent transverse walls.

It is also possible to facilitate the placing of metallic reinforcements intended to be placed in a wall by breaking the hems of the transverse walls at parts having a smaller thickness. These parts are produced for example by the existence of slots 25 in these transverse walls. These slots or grooves also serve for anchoring the concrete which may be located in the hollows 16.

The constructional block according to the invention might have its transverse walls at other places than those which have been indicated above with regard to the block of Figure 1. In Figure 4 another block in accordance with the invention has been shown, in which the transverse walls have their middle plane at a distance from the end faces equal to a quarter of the length of the block. The holes 11 are formed in the centre of the length of the block, and in halves in the end faces of the latter.

In Figure 5 another block according to the invention has been represented, which is of half the cross-sectional area of the block of Figure 1. In this case only slots such as the slots 8 and 9 serve to form, by the juxtaposition of two blocks, slots intended for the casting of cement effecting the connection between the blocks.

In building partition walls of smaller thickness than an external wall, it would obviously be possible to use thinner blocks than those which normally serve for the construction of external walls.

It is also evident that blocks of half the thickness of the blocks used normally for the construction of external walls, and open to the interior may be employed with advantage at the levels where floor layers rest on the walls of a structure.

The invention is not exclusively limited to the forms of construction represented, and many modifications may be made in the form, arrangement and constitution of certain of the elements involved in its realization, in so far as such modifications do not contradict each of the following claims.

The channels such as 10, which, in the case of the embodiments shown, are completely formed in the lower face of the block according to the invention, might also be formed completely in the upper face of the block, or partly in the lower face of one block and partly in the upper face of the block below it. It will be understood that in practice it is preferable for ease of construction, to provide these channels entirely in one face.

What I claim is:

1. A hollow constructional block comprising vertical

longitudinal walls, vertical transverse walls connecting said longitudinal walls, horizontal faces perpendicular to said longitudinal and transverse walls, said transverse walls having cavities therein extending throughout their entire height and substantially their entire length, one of said longitudinal walls having a hole therein extending throughout the entire height of said block and positioned substantially midway between two adjacent transverse walls and one of said horizontal faces having channels therein extending from said cavities to said hole.

2. A hollow constructional block comprising vertical longitudinal walls, vertical transverse walls connecting said longitudinal walls, horizontal faces perpendicular to said longitudinal and transverse walls, said transverse walls having cavities therein extending throughout their entire height, one of said longitudinal walls having a hole therein extending throughout the entire height of said block and positioned substantially midway between two adjacent transverse walls, one of said horizontal faces having channels therein extending from said cavities to said hole and the longitudinal wall opposite to that in which said hole is formed being of less thickness in the vicinity of said transverse walls.

3. A hollow constructional block comprising vertical longitudinal walls, vertical transverse walls connecting said longitudinal walls, horizontal faces perpendicular to said longitudinal and transverse walls, said transverse walls having cavities therein extending throughout their entire height, one of said longitudinal walls having a hole therein extending throughout the entire height of said block and positioned substantially midway between two adjacent transverse walls, one of said horizontal faces having channels therein extending from said cavities to said hole and the longitudinal wall opposite to that in which said hole is formed having passages extending throughout the entire height of said block in the vicinity of said transverse walls.

4. A hollow constructional block comprising vertical longitudinal walls, vertical transverse walls connecting said longitudinal walls, horizontal faces perpendicular to said longitudinal and transverse walls, said transverse walls having cavities therein extending throughout their entire height, one of said longitudinal walls having a hole therein extending throughout the entire height of said block and positioned substantially midway between two adjacent transverse walls, one of said horizontal faces having channels therein extending from said cavities to said hole and the external face of the longitudinal wall opposite to that in which said hole is formed having grooves therein extending the entire height of the block in the vicinity of said transverse walls.

5. A hollow constructional block comprising vertical longitudinal walls, vertical transverse walls connecting said longitudinal walls, horizontal faces perpendicular to said longitudinal and transverse walls, said transverse walls having cavities therein extending throughout their entire height, one of said longitudinal walls having a hole therein extending throughout the entire height of said block and positioned substantially midway between two adjacent transverse walls, one of said horizontal faces having channels therein extending from said cavities to said hole, the external face of the longitudinal wall opposite to that in which said hole is formed having grooves therein extending the entire height of the block in the vicinity of said transverse walls and the grooves formed in the part of a longitudinal wall between two adjacent transverse walls having their external side faces forming bevels which converge outwardly.

6. A hollow constructional block comprising vertical longitudinal walls, vertical transverse walls connecting said longitudinal walls, horizontal faces perpendicular to said longitudinal and transverse walls, said transverse walls having cavities therein extending throughout their entire height, one of said longitudinal walls having a hole therein extending throughout the entire height of said block and positioned substantially midway between two adjacent transverse walls, one of said horizontal faces having channels therein extending from said cavities to said hole and the parts of the longitudinal walls between two transverse walls being of less thickness at certain places near the horizontal faces.

7. A hollow constructional block comprising vertical longitudinal walls, vertical transverse walls connecting said longitudinal walls, horizontal faces perpendicular to

said longitudinal and transverse walls, said transverse walls having cavities therein extending throughout their entire height, parts of the transverse walls being of less thickness at certain places near the horizontal faces, one of said longitudinal walls having a hole therein extending throughout the entire height of said block and positioned substantially midway between two adjacent transverse walls and one of said horizontal faces having channels therein extending from said cavities to said hole.
